UNITED STATES PATENT OFFICE.

JOHN F. FARMER, OF INDIANAPOLIS, INDIANA.

REFLEX-ACTION MOTOR-VEHICLE LAMP.

Application filed September 2, 1926. Serial No. 133,275.

This invention relates to a type of motor-vehicle lamp that is designed as an anti-glare electric lamp having reflex action whereby a roadway may be illuminated with 5 out projecting light beams into the eyes of motor-vehicle operators approaching from an opposite direction, the invention having reference more particularly to an anti-glare lamp having various improved features 10 whereby to obtain improved results in projecting a strong light beam straight ahead on a road and also reflecting light on only one side of the road.

An object of the invention is to provide an 15 improved electric lamp which shall be so constructed as to be adapted for use in various ways not only to illuminate a roadway efficiently, but also as a spot-light when desired, while being capable of protecting opposing 20 drivers against blinding lights.

Another object is to provide an improved 25 anti-glare electric lamp which shall have an improved reflecting means and which shall not be costly, but shall be adapted to be used as a separate unit or in association with the customary pair of headlights to be switched on as may be desired when switching off the pair of lamps.

A further object is to provide an improved 30 guarded spot-light reflector and a simple casing for the reflector and the necessary electric lamp, which shall be of such construction as to be small and compact and adapted for projecting a light beam ahead beyond the casing 35 substantially parallel to the initial beam projected directly from the lamp, for the protection of drivers of other motor-vehicles on public highways.

With the above-mentioned and other objects in view, the invention consists principally in a novel reflex action reflector and its arrangement for projecting light on the roadway in an improved manner, the invention consisting also in an improved lamp casing 45 and its arrangement relatively to a motor-vehicle; and further, in the novel parts and in the combinations and arrangements of parts, as hereinafter particularly described and further defined in the appended claims.

Referring to the drawings—Figure 1 is a 50 fragmentary top plan of the forward portion of an automobile having the customary headlight lamps and provided with the improved separate anti-glare lamp in a convenient arrangement thereof; Fig. 2 is an enlarged side view of the improved lamp unit and its sup-

porting device; Fig. 3 is a horizontal central section of the improved lamp; Fig. 4 is an elevation of the improved lamp stand partially broken away; and Fig. 5 is a vertical 60 central section of the improved stand.

Similar reference characters in the various figures of the drawings indicate corresponding elements or features of construction herein referred to in detail.

The improved lamp is illustrated as arranged on the forward portion of a motor-vehicle as it may be conveniently carried. When applied to motor-vehicles already equipped with a pair of lamps the anti-glare 70 lamp preferably is arranged in proximity to the left-hand side of the motor. The numeral 1 indicates the forward end portion of a motor-vehicle, 2 and 3 the forward carrying wheels, 4 representing the left-hand lamp which is partially broken away, 4' representing the right-hand lamp.

The casing of the improved lamp preferably is substantially bowl-shaped, comprising a bottom or back portion 5 and a wall 80 portion 6, the latter having an outwardly extending window frame flange 7 on its edge portion. A portion of the wall 6 which is normally the rearward portion, has an aperture 8 therein. A boxing comprising a cylindrical main portion 9 is secured to the wall 6 so as to encircle the aperture and it has a conical end portion 10 provided with a guide collar 11 to support a lamp socket.

An improved parabolic reflector 12 is illustrated which is provided centrally with a deeply dished or depressed portion 13 to receive a portion of an electric lamp and to conveniently serve to assist in supporting the lamp, being centrally provided with a 90 neck 14 aligning with the collar 11 when the reflector is secured in the casing so that the neck is received into the aperture 8. A lamp socket 15 is adjustably arranged and supported in the collar 11 and the neck 14 and secured in place by means of a set-screw 16 arranged in the collar 11 to engage the socket. The socket has a conventional head 17 in which the terminals of electric circuit wires 18 are arranged in a conventional manner. The shank or plug 19 of an electric lamp bulb 20 is suitably secured in the socket 15 and may be moved longitudinally by the socket for focusing the lamp in the reflector. The line 21 indicates the larger end of the parabolic reflector, and the larger end portion is of such diameter as to project out beyond the

casing, but is cut away so as to have a receding edge portion 22 adapting it to conform to the form of the casing, the back of the reflector having a crescent anchor plate 23 fixed thereto that is seated against the flange 7.

In the normal position of the lamp casing in use that portion of the wall 6 opposite to the lamp is to be considered as the front of the casing, the back 5 being the left-hand side, 10 so that the casing has in effect a large window frame and opening in the normal right-hand side thereof and on an inclined angle relatively to the line of movement of the motor-vehicle.

15 A reflex-action reflector is arranged in the normally forward portion of the casing which, though functionally different from the parabolic reflector may be structurally integral therewith so as to constitute a portion 20 of a complete reflector structure. The reflexing reflector has a side reflector portion 24 that is deeply concaved and a reflexing portion 25 that is slightly concaved, and a supporting portion 25', the portions 24 and 25' 25 being curved to correspond to the curvature of the edge portion of the parabolic reflector and being connected thereto, either integrally or otherwise. The edge of the portions 25 and 25' being a continuous marginal portion, 30 has a flange 26 that is on one and the same plane with the flange 23 and is seated against the flange 7. Preferably a packing ring or gasket 27 is arranged on the front of the reflector flange and directly supports the edge 35 portion of a concavo-convex window-glass 28 which covers the opening in the casing and protects the inside of the reflector. A retaining ring 29 embraces the edge of the window-glass and is suitably shaped to engage the casing flange 7 and the front of the window-glass, the ring being non-continuous and provided on its outer side with ears 30 and 31 to 40 which a coil spring 32 is connected to forcibly contract the ring, but permitting expansion of the ring to remove it and the window-glass from place when renewal of the electric lamp is required.

45 For the purpose of advantageously mounting the lamp on a motor-vehicle in a convenient position and so as to be adjustable, the normally under portion of the casing is provided with an adjusting stand which preferably comprises a base 33 secured to the casing and having a neck 34 that normally projects downwardly and has a bearing ball 35 thereon. The ball is embraced by a ball joint socket composed of two halves 36 and 37, one 50 of the half parts having a stand portion 38 and the other a relatively longer stand portion 39, the stand portions having ears 40 and 41 that are detachably connected together by means of bolts 42 by which the socket parts are held more or less tightly on the socket

55 joint ball 35 to securely hold the ball when adjusted. The stand parts 38 and 39 have base flanges 43 and 44 thereon which together constitute a supporting base which preferably is inclined to the vertical axis of the socket to correspond to the inclination of a part of the motor-vehicle where it may be preferred to 60 carry the lamp.

65 In practical use the main lamps 4 and 4' when present on a motor-vehicle are used for lighting the road but may be switched off at will, and should be switched off or dimmed on 70 approaching another vehicle on the road. The improved lamp may be used continuously if desired, or alternately when the other lamps are so bright as to interfere with an approaching driver. The casing of the improved lamp effectively prevents an approaching driver from seeing the lamp in the reflector. The light from the lamp is projected onto the portion 25 of the reflexing reflector 75 and turned back onto the parabolic reflector 80 at one side of the lamp, and the parabolic reflector in turn projects a beam through the window-glass and past the farther portion of the casing, so that a strong beam of light is projected straight ahead of the motor-vehicle 85 approximately parallel to the beams that are projected directly from the lamp to the reflexing reflector. At the same time the various portions of the reflector project rays laterally on the roadway to illuminate the right-hand side of the road. The lamp may be 90 readily adjusted to change the direction of light beams as may be found desirable to suit 95 conditions of operation.

100 What is claimed as new is:

1. A motor-vehicle lamp including a bowl-shaped casing having an opening, a parabolic reflector arranged in the casing and having a relatively small central depressed portion to support a lamp bulb, the reflector having an edge portion projecting through the opening in the casing, a reflexing reflector arranged in the casing opposite to the depressed portion of the parabolic reflector, and a window-glass 105 arranged to cover said opening outside the projecting portion of the parabolic reflector.

110 2. In a motor-vehicle lamp, the combination of a bowl-shaped casing having a boxing thereon provided with a collar, the casing having a relatively oblique-angled window in its side, a parabolic reflector arranged in the casing and having a depressed central portion projecting partially into the boxing, the depressed portion having a neck thereon, a lamp socket adjustably supported in said neck and said collar, and a reflexing reflector arranged in the casing opposite to the lamp socket and obliquely to the parabolic reflector.

115 In testimony whereof, I affix my signature on the 27th day of August 1926.

JOHN F. FARMER.
